US0D1060986S

(12) United States Design Patent (10) Patent No.: US D1,060,986 S
(45) Date of Patent: * Feb. 11, 2025

(54) SHOE

(71) Applicant: NIKE, Inc., Beaverton, OR (US)

(72) Inventor: Brenton Wehrmeyer, Portland, OR (US)

(73) Assignee: NIKE, Inc., Beaverton, OR (US)

() Term: 15 Years

(21) Appl. No.: 29/887,696

(22) Filed: Mar. 23, 2023

(51) LOC (15) Cl. 02-04

(52) U.S. Cl.

USPC D2/954; D2/955

(58) Field of Classification Search

(57) CLAIM

The ornamental design for a shoe as shown and described.

DESCRIPTION

FIG. 1 is a front bottom perspective view of a shoe showing my new design;

FIG. 2 is a bottom view thereof;

FIG. 3 is a rear bottom perspective view thereof; and,
FIG. 4 is a cross-section taken through the line 4-4 in FIG. 2.

The broken lines depicting the remainder of the shoe form no part of the claimed design.

1 Claim, 4 Drawing Sheets
